US00D916777S

(12) **United States Design Patent** (10) Patent No.: **US D916,777 S**
(45) Date of Patent: **** Apr. 20, 2021**

(54) **DISPLAY SCREEN WITH GRAPHICAL USER INTERFACE**

(71) Applicant: **KONINKLIJKE PHILIPS N.V.**,
Eindhoven (NL)

(72) Inventors: **Wee Kar Tan**, Medford, MA (US);
Jacco Christof Eerden, Eindhoven
(NL); **Christopher Edward**
Haverstock, Melrose, MA (US);
Luciano Arnold, Cambridge, MA (US);
Kristen Deveau, Cambridge, MA (US);
Vladimir Ivashin, Cambridge, MA
(US)

(73) Assignee: **KONINKLIJKE PHILIPS N.V.**,
Eindhoven (NL)

(**) Term: **15 Years**

(21) Appl. No.: **29/666,569**

(22) Filed: **Oct. 15, 2018**

(51) LOC (13) Cl. **14-04**

(52) U.S. Cl.

USPC **D14/486**

(58) Field of Classification Search

USPC D14/485-495

CPC G06F 3/048
